UNITED STATES PATENT OFFICE.

BENJAMIN ZEICHNER, OF BROOKLYN, NEW YORK, ASSIGNOR TO L. & H. STERN, INC.,
OF BROOKLYN, NEW YORK, A CORPORATION OF NEW YORK.

SMOKING PIPE.

Application filed January 16, 1922. Serial No. 529,643.

To all whom it may concern:

Be it known that I, BENJAMIN ZEICHNER, a citizen of the United States, and a resident of the city of New York, borough of Brooklyn, county of Kings, and State of New York, have invented an Improvement in Smoking Pipes, of which the following is a specification.

This invention relates to smoking pipes, 10 and particularly to that class of pipes wherein a chamber or well is provided adjacent the bowl and between the bowl and stem.

In the drawings I have illustrated one embodiment of my invention, and inasmuch 15 as this embodiment is selected for the convenience of illustration I do not wish to be limited to the particular construction therein shown, as it is obvious that the invention may take many forms within the scope of 20 the claims.

Figure 1 is an illustrative embodiment of a pipe formed in accordance with this invention;

Figure 2 is a sectional view thereof; and 25 Figure 3 is a sectional view of the bottom of the bowl.

The illustrative embodiment of the invention includes a shank 10, which is provided at one end with an enlargement 11, 30 in which a chamber or well 12 is formed. This chamber opens upwardly for communication with the bowl of the pipe. A duct 13 communicates with the chamber or well 12, extends through the shank 10, and 35 communicates with the duct in the stem 14. This stem 14 is attached to the shank 10 by any of the well-known methods of attachment.

The bowl is mounted on the enlargement 40 of the shank 10, so that the recess or chamber which accommodates the combustible substance is aligned with the chamber or well 12. This bowl consists of two parts, one being the side wall 15, by which the chamber or recess 16 is bounded, and the other being the bottom 18. This bottom 18 of the bowl is provided with two oppositely extending projections 19 and 20, the projection 19 extending into the recess or chamber 45 16 and being detachably engaged with the wall 15, and the projection 20 extending into the chamber or well 12 and being detachably engaged with the shank 10. The bowl and shank are thus detachably held together. While I have illustrated the pro-

jections 19 and 20 as screw-threaded and engaging corresponding threads in the wall 15 and in the shank 10, it is obvious that a push or other frictional connection may be substituted for the screw-thread connection. 60

In order to limit the movement of the projection 18 into the recess 16 and the movement of the projection 20 into the chamber or well 12, a flange 21 is provided on the bottom 18 which flange is seated in a 65 recess at the lower end of the wall 15, and is of a diameter less than the diameter of the lower portion of the wall, so that when the material of which the bottom of the bowl is made is a good conductor of heat 70 the hand of the user of the pipe will be protected by the overlying portion of the wall 15.

The bottom of the bowl in the form illustrated in the drawing has a recess 22 75 therein, which forms the lower end of the recess 16 of the wall 15 and communicates with the chamber or well 12 through a duct 23.

It has been found that in pipes of the 80 class where a chamber or well is located adjacent the bowl and between the latter and the stem, if the bottom of the bowl is made of the ordinary combustible material, such as briar, the bottom will very quickly burn 85 out and thus render the pipe valueless: but where the bottom of the bowl is made of a non-combustible material the heat generated during the smoking of the pipe will, of course, be ineffective to destroy the bottom. 90 With this construction the wall of the pipe may, of course, be made of briar to retain the virtues incident to the use of briar in the bowl, and the bottom of the bowl may be made of any non-combustible material, 95 such as metal or, in fact, any of the well-known materials used where heat resistance is of importance.

The stem and shank of the pipe may be 100 made of any suitable material, such as hard rubber, horn, redmanol, bakelite, amber, briar, etc. Or the stem may be made of any one of these materials and the shank of any of the others. For instance, the shank may be made of briar and, since the flange 21 on the bottom of the bowl does not project through the side wall of the bowl, the continuity of the briar bowl will be preserved. The formation of the various parts of the pipe of any of these or other materials is, 105 110

however, a matter of choice and unimportant except that the bottom of the bowl must be formed of a heat-resisting or non-combustible material.

5 It will of course be understood that the bowl may have communication with the chamber or well 12 through a series of ducts arranged in various manners, instead of through one duct, as illustrated in the drawing.

10 With a pipe constructed in this manner all of the advantages incident to the use of a chamber or well adjacent to the bowl and between the bowl and the stem are retained, and, in addition, the bottom of the bowl is 15 prevented from burning during the smoking of the pipe.

What I claim is:

1. A smoking pipe comprising a shank 20 terminating at one end in an enlarged portion provided with a chamber, a top member conformed to said enlarged portion, and a connecting member comprising a relatively deep receptacle having a bottom wall portion materially thicker than the side wall 25 portions thereof, and an elongated passage extending vertically through said bottom portion, substantially as specified.

2. A smoking pipe comprising a shank 30 terminating at one end in an enlarged por-

tion provided with a chamber, a top member conformed to said enlarged portion, and a connecting member comprising a relatively deep receptacle having a thin side wall portion extending into and secured to 35 said top member, and a relatively thick bottom wall portion extending into and lying wholly within said chamber and secured to said shank, and an elongated passage extending vertically through said bottom portion, substantially as specified. 40

3. A smoking pipe comprising a shank terminating at one end in an enlarged portion provided with a chamber, a top member conformed to said enlarged portion, and a connecting member comprising a relatively 45 deep receptacle having a thin side wall portion extending into and secured to said top member, and a relatively thick bottom wall portion of reduced cross section extending 50 into and occupying the major portion of said chamber and secured to said shank, and an elongated passage extending vertically through said bottom portion, substantially 55 as specified.

In testimony whereof I have signed my name to this specification this 14th day of January, 1922.

BENJAMIN ZEICHNER.
